Kloss, Stenger & LoTempio; David T. Stephenson

(21) Appl. No.: **29/534,683**

(57) **CLAIM**

(22) Filed: **Jul. 30, 2015**

The ornamental design for fabric containment device, as
shown and described.

(51) **LOC (10) Cl.** **11-07**

DESCRIPTION

(52) **U.S. Cl.**

FIG. 1 is a front perspective view of a fabric containment
device showing our new design in a position of use on a
shirt;

(53) **USPC** **D11/200**

FIG. 2 is a rear perspective view shown in a position of use
with a scarf;

(58) **Field of Classification Search**

FIG. 3 is a front perspective view, shown in a disassembled
position;

USPC ..... D11/1-2, 200-218; 24/163 R, 169-171,
24/173, 177-179, 191, 194-195, 197,
24/200, 614-616, 625, 198, 578.11,
24/578.1, 163 K, 114; 2/236, 300

FIG. 4 is a rear perspective view of FIG. 3;

CPC A44B 11/26; A44B 11/25; A44B 11/06;
A41F 19/00

FIG. 5 is a top plan view of FIG. 3;

See application file for complete search history.

FIG. 6 is a bottom plan view of FIG. 3;

(56)

FIG. 9 is a rear elevational view of FIG. 3;

FIG. 10 is a front perspective view shown in an assembled
position with the non-claimed environmental matter;

FIG. 11 is a rear perspective view of FIG. 10;

FIG. 12 is a top plan view of FIG. 10;

FIG. 13 is a bottom plan view of FIG. 10;

FIG. 14 is a left side elevational view of FIG. 10, the right
side being a mirror image;

FIG. 15 is a front elevational view of FIG. 10; and,

FIG. 16 is a rear elevational view of FIG. 10.

The broken line showing of a shirt, a scarf and model, and
attachments is included for the purpose of illustrating envi-
ronmental matter only and forms no part of the claimed
design.
